BUILDING CONSTRUCTION

Everett H. Fuller, East Walpole, Mass., assignor to
 Bird & Son, Inc., East Walpole, Mass., a corpora-
 tion of Massachusetts

Application May 22, 1942, Serial No. 444,055

2 Claims. (Cl. 20—5)

This invention relates to building corner construction and is concerned with the provision of preformed corner elements which may be attached to the outside of a building, usually in vertical series, to form an imitation brick, stone or wood corner construction having improved characteristics from the standpoint of economy, appearance, and sealing of the corner against ingress of rain and snow.

The corner elements of this invention are especially adapted for use at the juncture of two building walls provided with ornamental siding strips of a type known to the art, one type thereof being formed with wide and narrow areas of differently colored adhesively affixed mineral granules giving a visual appearance of alternate areas of brick or stone and mortar or wood; and these corner elements are especially designed to carry out the brick, stone or wood imitation at the juncture of said walls. It is the purpose to include in the scope of this invention, both the mineral granule surfaced type of mortar line, and that in which the mortar line is burned or branded into the mineral granule covered asphalt coating.

For the purposes of simplification and economy, the corner element of this invention may be formed with a base which is composed of fibreboard and is so constructed and reinforced that the element maintains its preformed angular configuration adapting it for application to the corner of a building, and yet possesses a certain amount of flexibility, due to the absence of any metallic reinforcement, permitting the unit to conform more readily with building irregularities.

In the accompanying drawings, the corner element is shown as a brick and mortar cap sheet type element applied to a wall construction having brick and mortar appearing siding strips.

Fig. 1 is a perspective view of a partially constructed outside building corner showing certain parts broken away.

Fig. 2 is a horizontal cross-section through the completed construction;

Figs. 3 and 3a are diagrammatic representations illustrating certain of the steps involved in one method of assembling the corner element;

Fig. 4 is a perspective view of a single outside corner element broken in the middle to indicate variable length

Fig. 5 is a partial view of an outside corner element showing parts adapted to interfit with parts of the corner element of Fig. 4 to provide

a vertical series of corner elements provided with a waterproof joint;

Figs. 6 and 7 are fragmentary vertical sections along the lines 6—6 and 7—7, respectively, of Figs. 4 and 5;

Fig. 8 is a vertical section of the construction taken generally along the line 8—8 of Fig. 1, but including an additional lower corner element; and

Fig. 9 is a diagrammatic representation similar to Fig. 3a, but illustrating a modified form of the invention providing a corner element adapted for use in inside corner construction.

As shown in Fig. 1, the wooden wallboards 2, forming a building juncture at an upright corner stud 4, are covered with imitation brick wall siding strips 6, which meet at the juncture as shown in Fig. 2. The siding strips are capped at the corner by fixing thereover the corner element 8 of this invention, preferably by nailing.

The corner element 8 is shown more in detail in Figs. 4 and 5 and comprises two sheets of fibreboard 10 and 12 fastened together and in bent nested relation as by staples 14 and 18, and impregnated or coated with a material such as asphalt or resin, which waterproofs and hardens the surface. The exterior surface of the impregnated sheet 10 is covered with a facing of a flexible sheet of asphalt-saturated felt 15 having an adherent surfacing of finely-divided mineral matter divided into horizontal stripes to provide a plurality of brick and mortar appearing portions of contrasting color and spaced in similar relation to the spacing of the brick and mortar appearing courses of the siding strips 6. As shown in Figs. 4 and 5, longitudinal edge portions 16 and 17 of the mineral covered asphalt-saturated felt are doubled around the longitudinal edges of the fibreboard sheet 10, and are fastened against the inside marginal portions thereof as by staples 18. Additionally, if desired, suitable adhesive material, such as asphalt, may be interposed between the sheets 10 and 15 to attach the granule coated sheet more securely.

In order to permit the use of several units 8 in vertical series without sacrifice of waterproofing qualities, I preferably form each corner unit in such manner that it is provided with opposite ends tongued and grooved, respectively, and adapted to complement and interfit with grooved and tongued ends, respectively, of adjacent units. For this purpose, I utilize a fibreboard sheet 10 and fibreboard sheet 12 of substantially equal length and of unequal width. As indicated in Fig.

3, these are stapled together with their ends in offset and stepped relation as indicated by Fig. 4, as by a row of rivets or staples 19 inserted substantially along the center line. The combined parts are then bent along the center line to the desired angle, as shown in Fig. 3a, and, after bending, additional staples 14 are inserted to maintain the composite fibreboard sheets in bent and nested relation. The combined sheets may then be waterproofed. Thereafter, as indicated by Fig. 4, in applying the outside mineral granule coated sheet 15, the sheet 15 is offset with relation to the ends of the fibreboard 10 so that one end of the element 8 will present an exposed tongue 20, being a portion of the fibreboard sheet 10, and the other end of the element 8 will present a groove 22 formed between the felt sheet 15 on one side and the extending ends of the doubled back marginal portions 16 and 17 of the sheet 15 together with the extending end 24 of the reinforcing inside fibreboard sheet 12, on the other side.

At some stage in the operations, the corners of fibreboard sheet 10 may be angled, as shown in Figs. 4, 5, 7 and 8, to facilitate insertion of the tongue 20 into a groove 22 of an adjacent element 8.

It will be noted that the inturned marginal portions 16 and 17 of the granule coated asphalt-saturated felt sheet are in substantially the same planes as the angled interior surfaces of the reinforcement 12 which, as shown, terminates inside of the marginal portions 16 and 17. Thus, in application of the corner element 8 to the building structure, it may be applied evenly and flush against the relatively smooth surfaces afforded at the building corner by the siding strips 6, 6, the reinforcing member 12 acting as a filler over the angled faces of sheet 10 between marginal portions 16 and 17. After the attachment of one corner element 8, an adjacent element may be fitted to it by the tongue and groove arrangements 20 and 22 to form a waterproof horizontal joint between the adjacent corner elements 8, especially effective if asphalt is present on the entire exterior surface of the fibreboard 10, including the tongue 20, as a result either of impregnation or of application as an adhesive for the attachment of the granule coated felt sheet 15.

Additionally, because of the flexible nature of the elements 8, comprised as they are of fibreboard and asphalt-saturated felt, without the interposition of metallic reinforcement, the elements will readily conform with any building irregularities.

As shown in Fig. 1, the corner elements 8 are so positioned relative to the mortar and brick courses of the siding strips 6, that the brick-appearing construction will be carried around the corner of the building. Furthermore, because the vertical, longitudinal edges of the element 8 are mineral granule coated, the juncture of the corner element with the siding strip will not be unsightly, as the brick and mortar appearing courses of the siding strips will meet similar courses of the corner element along a single vertical line without intervening space.

While the foregoing description has been confined to the cap sheet type of corner element, i. e. with the asphalt-saturated felt sheet 15, it

is to be understood that a similar corner element construction may be formed by affixing directly to the exterior surface of the composite formed by the fibreboard sheets 10 and 12, a coating of asphalt with mineral granules embedded therein, and with or without burned-in or branded mortar lines. In such cases, the doubled over portions 16 and 17 of the cap sheet 15 shown in the drawings will of course not be present, but a ship-lapped joint between the elements will be provided. It is also to be understood that the construction is equally applicable for use in the formation of corner elements which have simulated masonry appearances other than that of brick and mortar, for instance those in which the appearance is one of stone or wood, or even shingles.

An essential similar type of corner element construction is illustrated by Fig. 9, but with the corner element being formed for use at an inside building corner. As there shown, the fibreboard sheets 10 and 12 of Fig. 3 have been bent in a direction opposite to that in which they are bent in forming the element shown in Fig. 3a. Thereafter, the cap sheet 15 is affixed over the exposed surface of the wide fibreboard sheet 10, and with the reinforcing fibreboard sheet 12 extending over the outside angle of the corner element. As will be understood, the element is therefore adapted to be placed over the longitudinal joint between siding strips meeting at an inside corner of a building construction.

If desired, a longitudinal wooden strip 19a, having an outside 90° angle, may be affixed to the fibreboard base at the apex of the bend of Fig. 3a, before affixing cap sheet 15, in order to provide a sharper corner, should it be found that the corner element angle is more rounded than desired.

I claim:

1. A flexible preformed building corner element comprising two substantially rectangular sheets of fibreboard of substantially equal length but of unequal width, bent along substantially their median lines and affixed together in nested relation, a sheet of simulated masonry asphalt-saturated felt positioned on the exposed surface of said wider board with opposite edges thereof doubled around the longitudinal edges of said wider board and flattened against the exposed marginal portions of the opposite surface of said wider board, and fastening means securing said doubled portions of said felt sheet in doubled position, said doubled portions presenting surfaces in substantially the same planes as adjacent exposed surfaces of the narrower sheet, with the narrower sheet acting as a filler to support said element intermediate said doubled portions.

2. A performed building corner element as claimed in claim 1, in which said wider board and said felt sheet are assembled with their ends in stepped relation, with said felt sheet projecting beyond said wider board at the same end thereof as said narrower board projects, to form a groove, and said felt sheet terminating short of said wider board at the end that the wider board projects beyond said narrower board to leave said wider board projecting to form a tongue for said element.

EVERETT H. FULLER.
